ATTORNEY.

UNITED STATES PATENT OFFICE

AUGUST C. SCHOEN, OF LANSDALE, PENNSYLVANIA

STOCKING INSPECTING DEVICE

Application filed October 20, 1931. Serial No. 569,903.

My invention relates to a new and useful stocking inspecting device of the general type disclosed in my prior Patent No. 1,764,986 and in my co-pending application 5 for Patent No. 441,813, filed April 5th, 1930.

Inspecting devices made along the general lines disclosed in the patent and application for patent aforesaid work by expanding the stocking to be inspected to render visible any 10 defects in the knitting, such as runs or the like, and to that end, a stocking is drawn over the expansible form and subsequently the form is actuated to expand or spread to stretch the stocking drawn thereover to permit minute inspection by the attendant or operator.

In using stocking inspecting devices of this 20 nature there is an element of risk and uncertainty due to the fact that if a defective stocking is drawn over the form, and the form is subsequently expanded, the defect in the stocking, such as a run, tends, when the stocking is stretched, to run down the entire length of the stocking.

25 Therefore, in inspecting stockings, it is necessary that the inspection be conducted in two steps or stages, one to reveal the larger and coarser defects, and the other to reveal the more minute or finer defects, so that if, 30 when the stocking is first drawn over the form and is slightly expanded, a run is disclosed, it will not be necessary further to inspect the stocking, and to prevent the extension of the run in the body of the stocking it is 35 immediately taken off the form without being further stretched. If, on the other hand, the preliminary stretching and inspection of the stocking does not reveal any defect, the secondary or final stretching of the stocking can 40 be had to permit of more minute examination.

It is, therefore, the purpose of my present 45 invention to produce a stocking spreading device which is provided with primary and secondary stretching or expanding mechanisms whereby the stocking can be spread in two successive operations for inspection purposes.

With the above ends in view, my invention 50 consists of an expansible frame and means

for actuating said frame, including means for partially expanding said frame and means for further and more completely expanding said frame, said two expanding devices being adapted to act on the same frame 55 independently of and successively to each other.

My invention further relates to various other novel features of construction and advantage, all as hereinafter described and claimed in connection with the accompanying drawings, in which:

Figure 1 represents a fragmentary view in side elevation of a stocking inspecting device embodying my invention. 65

Figure 2 represents a diagrammatic view taken substantially on line 2—2 of Figure 1.

Figure 3 represents an end elevation of Figure 1.

Figures 4 and 5 represent sections on lines 70 4—4 and 5—5 respectively of Figure 1.

Figure 6 represents a plan view of a dog 75 cooperating with the foot pedal shown in Figure 4.

Referring to the drawings in which like 80 reference characters designate like parts, 1 designates a horizontal frame supported on the vertical legs 2 which are connected at their lower portions by the horizontal angle iron 3 which forms a frame or support for the operating mechanism to be hereinafter described. Supported by the upper horizontal frame 1 and the vertical legs 2 is an inner solid plate or frame 5 which is carried by the sleeve or collar 6 loose on the shaft 7, 85 which shaft is suitably journaled in the frame 1 or 2 in any desired manner. To the inner solid plate or frame construction 5 is secured an outer expansible frame 8 by means of the pivotal links 9. The outer frame 8 is provided with a front knob 11 which is adjustably secured thereto as at 12.

The outer frame 8 is mounted on the rigid arm or plate 13 by means of any suitable anti-friction devices 95 14, the plate 13 being rigidly carried by the upper horizontal frame 1. 15 designates a sliding block, to which is secured one end of the operating rod 16, the other end of which is pivoted to the arm 18 of a bell crank lever pivoted to the upper horizontal frame 1 at 100

19. 21 designates a spring connected to the arm 18 of the bell crank lever referred to, and anchored at any suitable point 22 of the horizontal and vertical frames 1 and 2. The 5 other arm 23 of the bell crank lever has pivoted thereto at 24 the operating rod or lever 25 which is provided with the bottom yoke 26 which is secured to the foot pedal 27 which is keyed at 28 to the bottom horizontal shaft 29. 10 30 designates another foot treadle which is loose on the shaft 29 and which registers or aligns with the dog 32 which is keyed to the shaft 29 at 33. The shaft 29 is suitably journaled in brackets 35 carried by the bottom 15 angle iron frame 3, as will be best understood from Figure 1. The operation is as follows: With the expandible frame 8 in its collapsed position shown in Figure 1, the operator draws the stocking to be inspected over said 20 frame with the knob 11 serving to spread or expand the toe portion of the stocking. When the stocking has been drawn over the frame 8, the operator depresses the left foot pedal 30 which is loose on the shaft 29 to 25 bring pressure to bear upon the dog 32 which is keyed to the shaft 29. This results in rotating the shaft 29 and thus pulling down on the operating lever 25 which in turn pulls down on the arm 23 of the bell crank lever, 30 the other arm 18 of which is secured to the horizontal arm 19 thereby pulling the sliding block 15 towards the left hand side of Figure 1, thus bringing pressure to bear upon the sleeve or collar 6 which is carried by the inner frame or plate 5 to move the latter to the left hand portion with respect to the stationary frame 8, to change the angular relation of the links 9 with respect to the inner rigid frame 5 and the outer rigid expandible frame 40 8, and thus expand or spread out the outer expandible frame 8. The extent of expansion of the frame 8 is obviously determined by the extent of the pull on the operating arm 25, the pull on which is in turn determined 45 by the rotation of the shaft 29. The rotation of the shaft 29 in this instance is limited by the contact of the left foot pedal 30 with the floor 36, and this preliminary expansion of the frame 8 serves to disclose the larger 50 defects in the stocking being inspected, and if the operator notices a run or a dropped stitch, the operator refrains from further expanding the stocking to prevent further running of the dropped stitch, and the defective 55 stocking is at once relegated to the repair department. In this way, the increase or exaggeration of defects is completely prevented, and minute inspection where it is not necessary is dispensed with. A second result 60 of the depression of the left foot lever 30 into contact with the floor 36 is that it brings down the right foot pedal 27, which is in a relatively high position, to about the level of the left foot pedal shown in Figure 1, thus rendering 65 the right foot pedal easily accessible to the foot of the operator. This takes place because the right foot pedal 26 is keyed to the shaft 29, as above stated. If on a preliminary inspection of the stocking, after the preliminary expansion resulting from the 70 operation of the left foot pedal 30, no defects are found, the operator then depresses the right foot pedal 27 down into contact with the floor line 35, thus further rotating the shaft 29 which is keyed thereto and further pulling down on the operating arm 25, thereby further actuating the sliding block 15 to press against the sleeve 6 further to push the inner frame or plate 5 to the left hand side of Figure 1, through the 75 instrumentality of the bell crank arm 18 and the actuating arm 16, further to expand the outer expandible frame 8 and further to stretch the stocking being inspected, to permit of minute examination to disclose such 80 defects as were not obviously visible as a result of the preliminary or partial spreading of the stocking which resulted from the depression of the left foot pedal 30. Obviously when the pressure on the foot pedals 27 and 30 is relieved, the spring 21 which is anchored to the arm 18 of the operating bell crank lever exerts a pull to the right hand direction of Figure 1, thereby moving the sliding block 15 through the connecting arm 16, also in a right hand direction, thus withdrawing the frame 5 in a right hand direction with respect to the expandible frame 8, to collapse the latter into the position shown in Figure 1, whereupon the stocking can be removed. 85 It is to be understood that the outer expandible frame 8 is loose on the sleeve 6, and that the sleeve 6 is loose on the shaft 7, and is connected to the sliding block 15 by any suitable 90 swivel connection, so that the inner frame 5 and the outer frame 8 may be rotated or revolved as a unit to permit the inspection of the stocking from all its sides. 95 It will thus be seen that my novel stocking inspecting device embodies a two-step expansion of the stocking to be inspected, the expansion accomplished at each step being 100 distinctly limited, and the two steps or operations being accomplished by the same mechanism, but successively and independently of each other. In describing my invention, I have shown an inner rigid frame 5 and an outer expandible frame 8, and have shown other details of construction of the frames 1 and 2, the spring 21, the connecting arm 16, 105 the sleeve 6, the sliding block 15, only for the purpose of clearly illustrating my invention, but it is to be understood that all of these and other parts are to be considered as illustrative rather than limiting the scope of my invention which primarily resides in the provision of two foot pedals, one to expand the stocking to a predetermined extent to permit of a preliminary examination, and to bring 110 the second pedal into operative relation pre- 115 120 125 130

paratory to the final expansion of the stocking for more complete examination, which final examination is accomplished by depression of said second pedal, both of these pedals 5 acting directly on a single unitary expanding mechanism.

Having thus described my invention, what I claim as new and desire to secure by Letters Patent is:

10. 1. A stocking inspecting device comprising an outer expandible frame, an inner actuating member operatively connected to said outer frame, a bell crank lever operatively connected to said actuating member, an operating arm connected to one link of said bell crank lever and to a foot pedal, a shaft to which said foot pedal is keyed, a second foot pedal loose on said shaft, and a dog fast on said shaft and registering with the underside of said second foot pedal, whereby the depression of said second foot pedal serves partly to depress said first mentioned foot pedal and partly to expand said outer frame by partial movement of said actuating member, the subsequent depression of said first mentioned foot pedal serving to complete the movement of said actuating member and resultant expansion of said outer frame.
25. 2. A stocking inspecting device comprising an outer expandible frame, an inner actuating member operatively connected to said outer frame, a bell crank lever operatively connected to said actuating member, an operating arm connected to one link of said bell crank lever and to a foot pedal, a shaft to which said foot pedal is keyed, a second foot pedal loose on said shaft, a dog fast on said shaft and registering with the underside of said second foot pedal, whereby the depression of said second foot pedal serves partly to depress said first mentioned foot pedal and partly to expand said outer frame by partial movement of said actuating member, the

subsequent depression of said first mentioned foot pedal serving to complete the movement of said actuating member and resultant expansion of said outer frame, and a spring connected to the other link of said bell crank 70 to return the inner actuating member and the outer expandible frame to their inoperative positions when the pressure on said foot pedals is relieved.

3. A stocking inspecting device including a support, transversely and longitudinally expandible elements carried thereby, and independently operable devices for actuating said elements in predetermined, intermittent 75 stages.

4. A stocking inspecting device including a support, expandible elements carried thereby, independently operable devices for actuating said elements in predetermined, intermittent stages, and means for automatically collapsing the expanded elements.

5. The combination with a stocking inspecting device having a movable member and longitudinally and transversely expandible elements carried by said member and adapted to be expanded thereby, of means for actuating said movable member and a plurality of independently successively operable actuating devices adapted to act on said means in predetermined, intermediate stages.

6. The combination with a stocking inspecting device having a movable member and longitudinally and transversely expandible elements carried by said support and adapted to be expanded thereby, of means for actuating said movable member, independently successively operable actuating devices adapted to act on said means in predetermined, intermediate stages, and means for automatically retracting said expandible 105 elements from the expanded position.

In testimony whereof I affix my signature.

AUGUST C. SCHOEN.
